UNITED STATES PATENT OFFICE.

JOHN HERALD, OF UNADILLA, NEW YORK.

DESIGN FOR BARN-DOOR HANGER.

Specification forming part of Design No. 5,368, dated November 21, 1871.

To all whom it may concern:

Be it known that I, JOHN HERALD, of Unadilla, in the county of Otsego and State of New York, have invented an Improved Design for Barn-Door Hanger; and do hereby declare that the following is a full, clear, and exact description thereof, which will enable others skilled in the art to make and use the same, reference being had to the accompanying drawing forming part of this specification.

The nature of my design is fully represented in the accompanying drawing to which reference is made.

Figure 1 is a front view of the hanger. Fig. 2 is a vertical section of Fig. taken on the line $x x$. Fig. 3 is a cross-section on the line $y y$.

A is the plate, which is fastened to the door, ornamented upon the outside, as seen in the drawing. B is the pulley, attached to the plate A by a pivot. C are screw-holes in the plate.

As seen in the figures the plate is bulged or swelled both longitudinally and transversely, the great swell being at or near the point where the lines $x x$ and $y y$ intersect.

I claim as my invention—

The design for a barn-door hanger, as shown.
JOHN HERALD.
